AUTOMATIC LOCK SLIDER

Davis Marinsky and Louis H. Morin, Bronx, N. Y.

Application September 5, 1941, Serial No. 409,635

11 Claims. (CL 24—205.5)

This invention relates to sliders used in conjunction with slide fasteners in coupling and uncoupling the stringers of such fasteners in the movement of the slider longitudinally of said stringers. More particularly, the invention relates to a lock slider employing an automatically actuated lock element as well as manually actuated means for moving the lock element into inoperative position in the operation of moving the slider along the stringers to uncouple the same. The novel features of the invention will be best understood from the following description and annexed drawing, in which certain embodiments of the invention are disclosed, and in which the separate parts are designated by suitable reference characters in each of the views; and in which:

Fig. 1 is a side and sectional view of a slider made according to the invention with part of the construction broken away.

Fig. 2 is a plan view of the structure as seen in Fig. 1, with part of the construction broken away and in section.

Fig. 3 is a view substantially similar to Fig. 1, the section being taken in a different transverse plane and also showing parts in a different position; and,

Fig. 4 is a perspective view of a lock element employed, detached.

In lock sliders of the kind under consideration it has been a common practice to employ a lock element as an integral part of a pull or other manually actuated member; and with devices of this type and kind, quite often it is experienced that the pull is supported in a raised position with respect to the slider wall by engagement of the pin or other part of the lock element with a link in such manner as to support the pull in said raised position. This experience has been objectionable, particularly in the laundering as well as the pressing of garments having this type of fastener device thereon. Oftentimes the slider or lock parts thereof have been rendered inoperative by bending or breaking the lock parts in the pressure applied thereto in passing through various types of laundering and pressing machines.

It is one of the distinctive features of our invention to provide a lock slider which will overcome the above and other objectionable characteristics in providing a lock element which does not interfere with the automatic return of the pull to a collapsed position upon the slider wall, and further in providing a lock element capable of movement independent of the pull, particularly in moving the slider longitudinally of the

stringers to couple the same by any other means or manner other than engagement of the pull. Still further, a lock element is provided which is free to move independent of the pull from an inoperative or raised position into an operative position in automatically locking the slider by stress or strain applied to the stringers tending to separate the same or to move the slider along the stringers in the opening direction.

In the accompanying drawing, one adaptation of the invention is shown. Considering Fig. 1, 10 represents a slider body of more or less conventional general form; that is to say, it comprises spaced top and bottom walls 11 and 12 joined at the wide end portion of the slider in a connecting web 13 with the walls of the slider having inwardly extending side flanges 14.

In the construction shown, the top wall 11, note Fig. 2, has transversely spaced bearings 15 between which the wall 11 is recessed as seen at 16, and one end of the recess opens into an elongated aperture 17 which opens into the channel 18 of the slider to engage the links of at least one stringer; one of the links being indicated in part in dot and dash lines 19 in Fig. 3 of the drawing.

As the stringer structure is well known in this art, no detail showing is made thereof.

At 20 is shown part of a finger piece or pull which may constitute any type and kind of a manually actuated member; and this pull has a yoke-shaped end formed by spaced bearing portions 21 pivoted to the bearings 15 by a pivot pin 22, the ends of which are riveted or otherwise secured to retain the pin against displacement.

Arranged upon the pin 22 between the bearing portions 21 of the member 20 is a substantially semi-cylindrical lock element 23 which might also be termed a hood element in that the outer curved wall of this element jackets the pivot pin intermediate the bearing portions 21. The element 23 includes end discs or bearing portions 24, apertured as seen at 25 to receive the pin 22. One of these end walls or discs includes an integrally projecting lock part 26, commonly referred to as the lock pin; and this pin is adapted to drop between adjacent links of a stringer in retaining the slider against movement thereon in one, or opening, direction. The element 23 also preferably includes at one edge wall of the curved portion thereof a projecting lip or flange 27 adapted to be engaged by the end portion 28 of the pull 20 in manually moving the element 23 into inoperative position; that is to say, to

draw the lock pin or part 26 out of the channel 18 of the slider into a position as indicated in Fig. 3 of the drawing, or a position beyond the position shown.

The wall of the hood lock element 23 is spaced beyond the pin 22 sufficiently to receive a coil spring 29 which encircles the pin 22, one end 30 of the spring engaging the element 23, and the other end 31 entering an aperture 32 in the recessed portion 16 of the slider, the spring tending to normally support the element 23 in the locked position shown in Fig. 1 of the drawing, with the lock pin or part 26 projecting into the channel 18.

In the normal locked position of the slider the hood portion of the element 23 substantially conceals the pin 22 as well as the spring arranged thereon, and in the normal operation of the slider, when it is desired to move the same along the stringers to couple the stringers, the raising of the pull or member 20 will automatically rotate the lock element and raise the lock pin or part 26 out of the channel 18 providing free movement of the slider along the stringers. Upon releasing the pull or member 20, the lock element then engaging the pull will automatically return the same to horizontal position with respect to the slider wall; and at the same time move the pin or part 26 into locked position. However, should the pin or part 26 strike the upper surface of a link which would retard or check movement of the element 23 into operative position, the pull or member 20 would automatically drop by gravity onto the slider, but leave the element in the position shown in Fig. 3. It will thus appear that in the laundering and pressing operations heretofore referred to, the danger of bending or breaking the lock element by the forcing of the pull or member 20 from a position substantially similar to that indicated in dotted lines in Fig. 3, to the full line position, is eliminated. The dotted line position represents the normal position that would be assumed by the pull if the pin part 26 were an integral part thereof; and with said pin part supported in the position illustrated in Fig. 3. It will also be apparent that when the stringers of the fastener are strained laterally tending to separate the same, if the parts of the slider are in the position shown in Fig. 3, the lock pin or part will automatically drop into position to engage the next link of the stringer to check further opening movement of the slider.

With the lock slider structure disclosed, it will be apparent that the pull or manually actuated member has a movement with as well as independent of the lock element; and in the construction disclosed, this element is disposed between the pivot ends of the pull. It will further be apparent that the lock element may have any type and kind of link engaging means to retain the slider against movement along the stringers.

Having fully described our invention, what we claim as new and desire to secure by Letters Patent, is:

1. A lock slider for separable fasteners, said slider comprising a channeled body formed by spaced walls, one wall having outwardly projecting and transversely spaced bearings, a pull pivoted to said bearings, a lock element swingably mounted on said pivot intermediate said bearings, said wall of the slider having an aperture opening into the channel thereof, a lock portion on said element operating in the aperture to enter the slider channel, tensional means cooperating with said element to normally sup-

port the lock portion in operative position, and means on said pull engaging said element to withdraw the lock portion thereof from the slider channel in swinging the pull on its pivot.

5 2. A lock slider for separable fasteners, said slider comprising a channeled body formed by spaced walls, one wall having outwardly projecting and transversely spaced bearings, a pull pivoted to said bearings, a lock element swingably mounted on said pivot intermediate said bearings, said wall of the slider having an aperture opening into the channel thereof, a lock portion on said element operating in the aperture to enter the slider channel, tensional means co- 10 operating with said element to normally support the lock portion in operative position, means on said pull engaging said element to withdraw the lock portion thereof from the slider channel in swinging the pull on its pivot, and said element comprising a hood-shaped body portion substantially concealing the pivot and said tensional means when the element is in operative position.

15 3. A lock slider for separable fasteners comprising a channeled body having spaced walls, a lock element movably supported on one of said walls and having a lock portion adapted to enter the channel of the slider through said wall, tensional means normally supporting the lock portion of said element in the channel of the slider, 20 manually operated means on said slider wall co-operating with said element to withdraw the lock portion thereof from said channel, said last named means being movable coaxially with and independent of said element, said lock element comprising a semi-cylindrical member enclosing said tensional means and having apertured end walls, and one of said end walls being extended to form said lock portion.

25 4. A lock slider comprising a channeled body having spaced walls, one wall of said body having a transverse recess intermediate end portions thereof, pintle bearings at terminal end portions of said recess, a pull having a yoke-shaped end defined by spaced apertured pintle bearings, a 30 pintle pin mounted in said bearings for pivotally supporting the pull on the slider wall, a lock element swingably mounted on said pintle intermediate the spaced bearings of said pull, said element having a lock portion operating in an aperture in said slider wall to enter the channel of the slider, a coil spring on said pintle and engaging said element to normally support the lock portion thereof in the channel of the slider, and interengaging means on the pull and element for operating said element to withdraw the lock portion from the slider channel in swinging the pull in one direction on said slider.

35 5. A lock slider comprising a channeled body having spaced walls, one wall of said body having a transverse recess intermediate end portions thereof, pintle bearings at terminal end portions of said recess, a pull having a yoke-shaped end defined by spaced apertured pintle bearings, a 40 pintle pin mounted in said bearings for pivotally supporting the pull on the slider wall, a lock element swingably mounted on said pintle intermediate spaced bearings of said pull, said element having a lock portion operating in an aperture in said slider wall to enter the channel of the slider, a coil spring on said pintle and engaging said element to normally support the lock portion thereof in the channel of the slider, interengaging means on the pull and element for operating said element to withdraw the lock portion from the slider channel in swinging the pull in

one direction on said slider, and said lock element comprising a hood-shaped body encircling the pintle and said spring intermediate the bearings of said pull.

6. A lock slider comprising a channeled body having spaced walls, one wall of said body having a transverse recess intermediate end portions thereof, pintle bearings at terminal end portions of said recess, a pull having a yoke-shaped end defined by spaced apertured pintle bearings, a pintle pin mounted in said bearings for pivotally supporting the pull on the slider wall, a lock element swingably mounted on said pintle intermediate the spaced bearings of said pull, said element having a lock portion operating in an aperture in said slider wall to enter the channel of the slider, a coil spring on said pintle and engaging said element to normally support the lock portion thereof in the channel of the slider, inter-engaging means on the pull and element for operating said element to withdraw the lock portion from the slider channel in swinging the pull in one direction on said slider, and said pull and element being each movable one independently of the other apart from said first named collective movement.

7. A lock element for sliders of separable fasteners, said element comprising an elongated semi-cylindrical body, the ends of said body having apertured walls, one of said walls having a protruding pin lock portion, and one side edge of said cylindrical body having a protruding lug portion.

8. In lock sliders for separable fasteners the combination with a pull pivoted to the slider for operating the same, of a lock element movably supported on the slider and mounted for coaxial rotation with the pull and having a lock part adapted to enter the channel of the slider, tensional means normally supporting the lock element in operative position and in engagement with said pull whereby in grasping the pull to operate the slider said element is actuated to withdraw the lock part from the slider channel, and means whereby said pull and element are independently movable on the slider.

9. The combination with the channeled slider

body of a separable fastener, of a swingable cylindrical lock element having a lock pin adapted to move into and out of the channel of said slider, a coil spring arranged within said element and cooperating therewith to normally support the pin in the channel of the slider, and manually actuated means rotatable coaxially with and independent of said element for withdrawing the pin part of said element from the slider channel.

10. A lock slider for separable fasteners comprising a channeled body, a pull for operating said body, means pivoting the pull to one wall of said body, said wall of the body adjacent the pivot of the pull having an aperture opening into the channel thereof, a lock element independently rotatable on the slider coaxially with the pull at said first named means, said element having a part engaging the pull whereby in moving the pull in one direction on the slider said element will be actuated, said element having a lock part operating in the aperture of said wall of the slider to move into and out of the channel thereof, and means normally supporting said element with the part thereof projecting into the slider channel.

11. The improvement in a slide for separable fasteners, said slide having spaced walls defining channels and one of said walls having an aperture thereon, which comprises pivot means carried by one of said walls; a pull mounted on said pivot means to rotate about the axis thereof and normally resting on said wall; a lock element having a hood portion, said element being pivoted on said pivot means to rotate thereon coaxially with and independently of said pull; said lock element having a detent portion extending through said aperture, resilient means enclosed within said hood portion to rock said lock element and to normally urge said detent into locking engagement with a fastener element, said lock element also having a portion normally overlapping said pull and adapted for engagement therewith to release said detent when the pull is rotated about said pivot.
